UNITED STATES PATENT OFFICE.

LOUIS LAMAGNA AND ALBOINO BOTTA, OF NEW YORK, N. Y.

CROSSING GATE.

Application filed May 23, 1928. Serial No. 280,052.

This invention relates to gates or barriers for a railroad, railway and other crossings.

The principal object of the invention is the provision of improvements in the construction and operation of gates and barriers of the indicated character, hereinafter fully described and illustrated in the accompanying drawings, in which—

Figure 1 is one of the gate units, at one of the approaches to the railroad, the gates being shown in the closed or obstructing positions.

Fig. 2 is a view similar to Fig. 1, but showing the gates in the open or non-obstructing positions.

Fig. 3 is a plan of a section of the unit indicated by the line 3—3 of Fig. 2.

Fig. 4 is a sectional view taken on the line 4—4 of Fig. 2.

Fig. 5 is a sectional view taken on the line 5—5 of Fig. 2.

Fig. 6 is a sectional view taken on the line 6—6 of Fig. 5.

Fig. 7 is a sectional view taken on the line 7—7 of Fig. 1.

Fig. 8 is a side elevation of a modified form of the invention, and shown partly in section.

The features of the invention shown in Figs. 1 to 7 inclusive of the drawings are applied in conjunction with a railroad and a crossing, by way of example. In accordance therewith it is to be understood that use will be made of two similar units respectively arranged at the crossing approaches to the railroad tracks on opposite sides with respect thereto so as to be operated by a train service member to close the gates which will remain closed while the train is passing, and to open the gates after the train has passed the crossing.

Inasmuch as each unit at each crossing approach will be similar in construction and operation, a description of the construction and operation of one of the units will suffice for both. The unit includes a fixed frame structure 10 built to the width of the crossing and sufficiently large to allow vehicles to pass therethrough. The said structure 10 comprises vertical side members 11, a central vertical member 12 and top horizontal members 13 which are connected together, and which are also connected with the upper ends of the vertical members 11 and 12. The lower ends of the members 11 and 12 are firmly anchored in the ground. Tilttable

supports 14 are arranged near the top of the frame structure 10, each of said supports 14 being tilttable by being pivotally connected at one end as at 15 to a portion of the frame structure 10. Means is arranged on the frame structure 10 which is operable to impart tilting movement to each of the supports 14. The said means includes a disk crank 16 supported for operation by a bearing 17 attached to the horizontal members 13. A band 18 loosely surrounds the circumferential edge of the disk of the crank. The end of each of the supports 14 remote from the pivoted end, is connected with a toggle joint 19, and the latter is connected with the band 18. Arranged to travel on each of the tilttable supports 14 into and out of a closed or obstructing position is a gate 20. The gate 20 is provided with a carrier or hanger 21, pivotally connected as at 22 in order that the carrier or hanger may tilt or rock. The carrier 21 is provided with rollers 23 which roll in contact with the support 14. A depending lug 24 is arranged on each end of the carrier 21. The frame structure 10 is provided with spring buffers or stops 25, there being one buffer or stop 25 on each of the outermost side members 11, and two respectively on opposite sides of the central vertical member 12. Each of the outermost side members 12 presents an abutment indicated at 26, and the central vertical member 12 also presents an abutment indicated at 27. It will be understood that when each gate 20 moved to the closed or obstructing position, one of the lugs 24 will encounter one of the buffers or stops 25 on the vertical member 12 and be cushioned thereby, and will be limited in its movement by contact with the abutment 27 to the closed or obstructing position. It will also be apparent that when each gate moves to the opened or non-obstructing position, the other lug 24 will encounter the buffer or stop 25 on the related member 11, thereby cushioning the same, the gate being limited in its movement to the opened or non-obstructing position by the abutment 26.

It will be apparent that when each support 14 is tilted to one position that its gate 20 will travel on the support 14 to a closed or obstructing position as shown in Fig. 1, and that when said support 14 is tilted to its other position, the gate 20 will travel on the support 14 to the opened or non-obstructing position, as shown in Fig. 2. The means hereinbefore referred to which serves for the pur-

pose of tilting the supports 14 is operated by a means presently to be described. The disk crank 16 has connected therewith an arm 28. A length of cable 29 is connected with the arm 28 as at 30. The cable 29 is guided for movement by sheaves 31 some of which are arranged on the frame structure 10, and others are operatively positioned in the road bed. Each end of the cable 29 is pivotally connected as at 32 with a track obstacle 33 secured to a rock shaft 34 supported by suitable bearings 35 attached to two of the railroad ties. Each of the obstacles 33 is positioned to be encountered by a train service member (not shown). The service member encounters one of the obstacles 33 which exerts a pull on the cable 29, which in turn exerts a pull on the arm 28, causing the disk crank 16 to operate, and as a consequence the 10 tiltable supports 14 will be moved to incline downwardly and inwardly toward the center of the frame structure 10. The gates 20 will then ride or travel on the supports 14 to the closed or obstructed positions as shown in 15 Fig. 1. When the cable 29 is pulled for the purpose of moving the gates to the closed or obstructing positions, the other obstacle 33 connected with the cable 29 will be brought to a position to be encountered by the train 20 service member, after passing the crossing. This will result in a reverse operation of the disk crank 16, and the tilting of the supports 14 to positions allowing the gates 20 to travel or ride on the supports 14 to the opened or 25 non-obstructing positions.

The closing of the gates 20 is accompanied by the sounding of an alarm in the form of a bell 36 attached to a portion of the frame structure 10, the said bell 36 being operated by a cable 37 or other flexible member. A portion of the cable 37 is wrapped around a rotor 38 forming a part of the bell 36, and which produces the ringing sound, and each of the ends of the cable 37 is connected with the carrier 21 of one of the gates, as at 39. The cable 37 is guided for movement by small sheaves 40 on portions of the frame structure 10.

In Fig. 8 of the drawing there is shown a modified form of the invention. In this form of the invention there is provided a barrier 41 provided with a shaft 42 journaled in a bearing 43 for the purpose of mounting

the barrier 41 for pivotal movement. One end of the barrier 41 has a weight 44 which serves for moving the barrier 41 to a normal nonobstructing position. A spool 45 is fast on the shaft 42. One end of a piece of cable 46 is connected with the spool 45, the opposite end is connected with a spring 47, and the spring is connected with a band 48 loosely surrounding the disk of a disk crank 49. The disk crank 49 has connected therewith an arm 50 which is pivotally connected as at 51 with a guide cable 52. Movement of the 65 cable 52 in one direction operates the disk crank 49 to exert a pull on the cable 46 bringing the barrier 41 to the obstructing position. When the cable 52 is moved in an opposite direction, the barrier is free to move 70 to the normal position under the influence of the weight 44, which causes the cable 46 to be wrapped on the spool 45 ready to be pulled to again bring the barrier 41 to the obstructing position.

We claim:

1. In combination, a fixed frame structure, tiltable supports on said structure, a disk crank on said structure, a band which cooperates with said disk crank, a toggle joint between said band and said supports to tilt said supports in response to the operation of said disk crank, a gate which travels into and out of obstructing position on each support by the tilting movements of the support, and obstacles connected with said disk crank and positioned to be operated to operate said disk crank.

2. In combination, a fixed frame structure, tiltable supports on said structure, a disk crank on said structure, a band which cooperates with said disk crank, a toggle joint between said band and said supports to tilt said supports in response to the operation of said disk crank, a gate which travels into and out of obstructing position on each support by the tilting movements of the support, an arm connected with the disk crank to operate the same, obstacles, each of said obstacles being connected with said arm by a cable having guided movement, each obstacle being mounted for movement to pull its cable to move said arm.
